UNITED STATES PATENT OFFICE.

HARRY S. WELSH, OF NEW YORK, N. Y.

COLLAPSIBLE FUNNEL.

1,247,354.

Specification of Letters Patent. Patented Nov. 20, 1917.

Application filed October 11, 1916. Serial No. 124,927.

To all whom it may concern:

Be it known that I, HARRY S. WELSH, a citizen of the United States, and a resident of New York, in the county of New York and State of New York, have invented certain new and useful Improvements in Collapsible Funnels of which the following is a specification.

This invention relates to improvements in devices for conducting fluids from one receptacle to another and particularly to types which are collapsible so that, when not in use, the same may be folded and stored in small compass, such devices being commonly known as funnels.

The principal object of the invention is to provide a funnel which may be readily attached to or detached from a convenient point of support, adjacent to the inlet of the vessel to be filled, the outer upper end of the funnel being expandable, so that fluids from a bucket or similar wide-mouthed dispensing vessel may be entered therein.

A further object is to provide such funnels with means whereby they may be firmly held when in an extended position, thereby avoiding the danger of an inadvertent collapse.

These and other objects, such as simplicity of construction, ease of application, and convenience in use, are attained by the novel construction and combination of parts hereafter described and shown in the accompanying drawings, forming a material part of this specification, and in which:

Figure 1 is a partial top plan view showing the funnel in an expanded position.

Fig. 2 is a side elevational view of the same.

Fig. 3 is a vertical sectional view taken on line 3-3 of Fig. 1.

Fig. 4 is a perspective view showing the device for holding the walls of the funnel in an open position.

Fig. 5 is a sectional view showing a means of attachment to the container.

Fig. 6 is a similar view showing a modified form of attaching means.

Fig. 7 is a partial side view showing a modification in attaching means.

Fig. 8 is a like view showing a different disposition.

Fig. 9 is a top plan view showing the funnel in a folded or collapsed position.

Fig. 10 is a similar plan view showing a modified form of funnel in its folded position, and

Fig. 11 is a fragmentary detail view of the construction shown in Fig. 10.

In all of the several views, the funnel is shown to be comprised of pairs of segmental metallic plates 10 and 12, respectively, outer and inner, connected along their lateral edges by flexible elements 14, secured by a row of rivets 15 so as to form a substantial imperious joint between each of the several segmental side walls.

In the present construction, the funnel is shown to be octagonal, having a normally widely spaced top opening 16, the lower or contracted end 18 being of a size adapted to be received within the connecting elements attached permanently to the filling nozzle or mouth of the container.

Secured upon alternate wall elements 12, 75 are perforated clips 20 having openings or eyes 21 in their extending ends adapted to receive the hook-shaped, down-turned terminals 22 of the arms 23, pivoted by the pins 24 in brackets 25, formed with an annulus 26, the annulus acting as a connection between the several arms, so that when the same are extended, as shown in Figs. 1 and 3, the walls are maintained in a substantially rigid condition and prevented from collapsing by reason of contact with the filling vessel as before indicated.

When the annulus is withdrawn, the segments forming the side walls, may be readily collapsed in an obvious manner, as shown in Fig. 9.

To the lower end of the segmental sides are attached bracket elements 30 having outward turned feet 31 adapted to be received in an annular groove 32, formed in an adapter 33, 95 screw threaded to the nozzle 35 of the container 36 as shown in Figs. 2 and 3. The flexibility of the segments is such as to permit the feet 31 to be readily entered into the groove, whereby the expander is placed in position, holding the funnel rigidly engaged in the grooves 31 of the adapter 33. In Fig. 5, the adapter 40 is shown to be of annular construction suited to be tightly fitted within the nozzle 35, the adapter containing an open annular slot 41, similar in all respects to the slot 32 before mentioned. In Fig. 6, the adapter 45 is suited to the screw threads

46, formed in the nozzle and contains a similar annular groove 47 to that previously described.

In Fig. 7, the adaptation shown varies 5 from the foregoing by the use of a flexible sleeve 50, engaged by any suitable means with the lower end of the funnel, the sleeve in turn being secured by rivets 51 to an annular ring 52, adapted to be engaged with 10 the container. When not in use, the sleeve, by reason of its flexibility, may be pushed upwardly into the funnel, as shown in Fig. 8.

Figs. 10 and 11 show a modified form of 15 funnel construction, in which single side elements 60, each having angularly disposed side edges, forming segmental plates, are connected along their edges by integrally formed hinges, engaged by a single pin element 61, and it will be evident that the 20 holding arrangements at the bottom of this modified form may be of a nature similar to that already described and that its operation is the same.

The principal object of the invention is 25 that of filling the radiators of internal combustion engines such as are used in connection with automobiles, boats and like vehicles, in which it is desired to maintain the

engine in a relatively cool condition, irrespective of the heat engendered by its action. 30 The usual construction of the reservoir for holding cool fluid, being such that difficulty is encountered in filling the same, hence the desirability of the means above described.

Having thus described my invention, what 35 I claim as new and desire to secure by Letters Patent, is:—

In a collapsible funnel, the combination with a plurality of rigid metallic plates each being wider at the top than at the bottom and having parallel top and bottom edges, said plates being flexibly joined along their lateral edges, perforated clips secured to the inner side of each alternate plate, hooks engageable in the perforations of said 40 clips, an annulus to which the inner ends of said hooks are hingedly engaged whereby said plates may be held in an expanded position, and means engaged with the lower end of said plates adapted to sustain the same 45 when in an expanded position.

Signed at New York, in the county of New York, and State of New York, this 30 day of Aug., 1916.

HARRY S. WELSH.
